CLAIM

The ornamental design for a wrap panel for use with a fuel dispenser, as shown and described.

DESCRIPTION

FIG. 1 is a perspective view from above illustrating the front and right side of a front wrap panel component of a fuel dispenser;

FIG. 2 is a front view of the front wrap panel of FIG. 1; FIG. 3 is a left side view of the front wrap panel of FIG. 1; FIG. 4 is a front view of a rear wrap panel of FIG. 1; FIG. 5 is a left side view of the rear wrap panel of FIG. 1; and,

FIG. 6 is a top view of the front wrap panel and the rear wrap panel of FIG. 1.

Where applicable, elements are shown in broken lines herein for illustrative purposes only, and form no part of the claimed design.

1 Claim, 6 Drawing Sheets
